UNITED STATES PATENT OFFICE

OTTO H. ESCHHOLZ, OF PITTSBURGH, PENNSYLVANIA, ASSIGNOR TO WESTINGHOUSE ELECTRIC & MANUFACTURING COMPANY, A CORPORATION OF PENNSYLVANIA

VACUUM CIRCUIT BREAKER

Application filed August 22, 1928. Serial No. 301,271.

My invention relates to circuit breakers and particularly to circuit breakers wherein the contact members of the circuit breaker are disposed in a vacuum.

An object of my invention is to provide a vacuum circuit breaker wherein ample space is provided for the expansion of the arc without directly coming in contact with the walls of the circuit breaker and wherein particles 10 discharged from the arc such as ions and electrons are intercepted before they reach the side walls of the enclosure, thus cooling the arc, deionizing the space in the vicinity thereof and freeing the space within the enclosure 15 of vapors incident to the volatilization of the contact members.

A further object is to so subdivide the arcing chamber that the length of any unobstructed path along lines of force of the electric field is less than the mean free path which 20 an electron must traverse in order to ionize the gas within said arcing chamber at the operating pressures therein.

A further object of my invention is to 25 provide a vacuum circuit breaker wherein the space between the point at which an arc is drawn within the contacts, and the side walls of the enclosure is less than the mean-free path of the electrons discharged from the arc 30 in order that the electrons shall be intercepted before they have reached velocities sufficient to ionize the space within the enclosure by collision with other particles.

A further object of my invention is to 35 provide a vacuum circuit breaker wherein the circuit breaker contacts are moved in the direction of the axes thereof and wherein the enclosure is relatively shallow in the direction of the movement of the contact members and wherein the side walls are disposed at relatively great distances from the point at which the arc is drawn, thereby providing an enclosure that is compact and efficient for 40 facilitating extinguishment of the arc.

A further object of my invention is to provide a vacuum type circuit breaker wherein part or all of the enclosing walls is made flexible to provide a diaphragm which may serve 45 as a support for the movable contact member

and which permits of full opening movement of the circuit breaker contacts.

A further object of my invention is to provide an improved means for mounting the stationary contact upon the enclosure and effectively sealing it to maintain a vacuum 55 tight vessel.

A further object of my invention is to provide a vacuum circuit breaker wherein is disposed an automatically operated "getter" 60 pump. The automatically operated getter pump serves to maintain a predetermined low pressure within the enclosure. Such means is a pressure responsive auxiliary arc established when the internal pressure exceeds a predetermined value, the arc serving 65 to actuate electrode material that absorbs the gases within the enclosure.

These and other objects that will be made apparent throughout the further description 70 of my invention are attained by means of the circuit breaker apparatus hereinafter described and illustrated in the accompanying drawings, wherein;

Figure 1 is a vertical section through a circuit breaker embodying features of my invention, and

Fig. 2 is a sectional view of a detail for insulating the intercepting barriers from the enclosure walls.

Referring particularly to Figure 1, the circuit breaker comprises a supporting frame 3 mounted upon insulating pillars 4 which may be connected to any suitable switchboard or frame structure. A shallow metal casing 5 serves as an enclosure for the relatively movable contact members 6 and 7, the former being mounted upon a terminal 8 secured by welding to a plate 9. The plate 9 is mounted upon an insulating pillar 11 which surrounds 85 the terminal 8, which rests upon the end wall 12 of the enclosure 5. A vacuum-tight connection between plate 9 and insulator 11 is effected by flexible flanges 13 which are welded or soldered to the insulator as well as to 90 the plate 9 and end wall 12 in a manner well known to those skilled in the art.

The movable contact 7 is mounted upon a terminal 14 which is supported on a flexible wall 15 of the enclosure 5, the wall 15 being 100

secured at its marginal edges by welding. The wall 15 is annular and made flexible by corrugations in order that a full opening movement of the movable contact 7 may take place without causing any portion of the wall 15 to be stressed beyond its elastic limit.

The terminal 14 carrying the contact 7 is biased to open position by means of a spring 16 disposed between the supporting member 3 and the free end of a lever 17 fulcrumed upon a pivot 18 mounted upon the support 3. The circuit breaker is maintained in a closed position by means of an electromagnet 19 that is energized through a control circuit 21. The operating mechanism for the circuit breaker is here illustrated more or less diagrammatically and it will be understood that the parts will be so designed and proportioned as to operate the contact terminal 14 under the pressure conditions existing when the enclosure is highly evacuated.

The plate 9 is yieldingly retained against displacement by means of a spring 22, the movement of the plate 9 being positively limited by an inwardly extending flange 23 disposed on the cover 24 which surrounds the insulating bushing 11. The space surrounding the insulating bushing 11 and the exposed portion of the contact terminal 8 is filled with an insulating liquid such as oil thereby reducing the over-all dimensions of the parts supporting the contact terminal 8 by reason of the superior insulating quality of the liquid compound as compared with air. The cap member 24 is made of insulating material and is provided with a flange 25 by means of which it is bolted to the end wall 12 of the enclosure 5.

It has been found that when an arc is formed in a high vacuum, its performance is radically different from that of an arc drawn in air at atmospheric pressures. The only gases present for supporting the arc are the vapors produced by volatilization of the contact members. Electrons are discharge laterally in all directions at relatively high velocities and ample space should be provided for the expansion of the momentary arc environment the separable contacts without its coming in contact with the walls of the enclosure.

The side walls of the enclosure are, therefore, disposed at a relatively great distance from the point at which the arc is drawn, the distance being less than the mean free path 55 of the electrons under the existing vacuum conditions, thereby reducing to a minimum, the collision of electrons tending to ionize the space within the enclosure.

Conical barriers 26 are disposed within the enclosure in substantially the manner illustrated in Figure 1, the barriers being superimposed and secured to the enclosure 5 by means of metal threaded inserts 27 that are embedded in an insulating block 28 that is secured to the enclosure wall by cement 29

as indicated in Figure 2. Screws 31 serve to secure the barriers 26 in assembled position.

It will be noted that the barriers extend angularly across the radial path of particles discharged from the arc drawn between the contacts 6 and 7 and serve to intercept the particles such as gas molecules and electrons and to thereby condense the gas molecules and to deionize the arc almost instantaneously after the formation thereof. The barriers intercept electrified particles before they have attained velocities sufficient to ionize by collision any remanent gas within the space. The space, therefore, is effectively deionized. The immediate proximity of the barriers to the arc stream provides surfaces upon which metallic vapor subliming at the electrode surface rapidly condenses, such vapors accordingly serving as getters for any gases present in the arc space or that may have been released from the contacts and from the materials constituting the enclosure walls.

The barriers 26 may be of insulating material or may be metallic and in either case their surfaces may be of a substance such as aluminum which has a good chemical affinity for such permanent gases as are likely to be present at any time in the enclosure. In such case the latter will be eliminated by chemical combination with the barrier surfaces. The barrier surfaces may also comprise a material adapted to be sublimed by the heat emanating from the arc and which on condensing produces a getter action.

By reason of the maintenance of the high vacuum and the deionized space surrounding the contacts, the arc will be permanently extinguished substantially at the instant when the zero potential of the voltage cycle is reached. After the arc has been extinguished, the high vacuum existing within the enclosure will prevent reforming of the arc even though the contacts are separated a relatively short distance apart.

The enclosure 5 is provided with a vacuum valve 32 of the type illustrated and described in U. S. Patent #1,223,736 issued April 24, 1917 through which the enclosure may be initially exhausted. Since no claim is made to this device, a detailed description is deemed unnecessary.

In order to maintain the high degree of vacuum desirable for operation of a vacuum circuit breaker, it is necessary to provide a means for eliminating the gases such as those which may be released from the contacts or the material constituting the enclosure. For this purpose, I have provided a getter pump 33 that comprises a pair of electrodes 34 made of calcium or some similar material the vapor of which readily condenses and which may therefore serve as efficient "getters" for any gases within the enclosure. A constant voltage is impressed upon the terminals of the electrodes 34 through the me-

dium of a transformer 35. The ends of the electrodes 34 are spaced apart a sufficient distance to cause an arc, which may be termed a "getter arc" to be drawn between them when 5 the pressure within the enclosure attains a predetermined value. The activated electrode material will absorb gases within the enclosure. When the pressure within the enclosure has been reduced sufficiently for 10 successful operation of the circuit breaker. the "getter arc" will automatically be extinguished for the lack of gaseous particles to sustain it.

It will be recognized that a pump of the 15 form just described is not the only one which may be employed in connection with my circuit interrupter and that other suitable pumps will be known to persons of skill in the art, which may be substituted for it.

20 While I have illustrated but one embodiment of my invention, it will be apparent to those skilled in the art that various changes, modifications, substitutions, additions and omissions may be made in the apparatus illustrated without departing from the spirit and 25 scope of my invention as set forth in the appended claims.

I claim as my invention:—

1. In a vacuum circuit breaker, an evacuated enclosure, a plurality of spaced superimposed annular barriers having substantially centrally disposed aligned openings extending transversely of the enclosure, and a pair of relatively movable contacts disposed 35 to draw an arc in a zone between at least two of the barriers so that the arc is substantially surrounded by the boundaries of the said openings, the boundaries of said openings being spaced from the electrodes a sufficient 40 distance to prevent contact of the arc-drawn between the electrodes with the barriers, and the barriers being so positioned as to intercept electrons and gases radiated from the arc toward parts of the enclosure unshielded by 45 the electrodes.

2. In a vacuum circuit breaker, an evacuated enclosure, a plurality of spaced superimposed frustro-conical barriers having substantially centrally disposed aligned openings extending transversely of the enclosure, and a pair of relatively movable contacts disposed to draw an arc in a zone between at least two of the barriers so that the arc is substantially surrounded by the boundaries 50 of the said openings, the boundaries of said openings being spaced from the electrodes a sufficient distance to prevent contact of the arc drawn between the electrodes with the barriers, and the barriers being so positioned 55 as to intercept electrons and gases radiated from the arc toward parts of the enclosure unshielded by the electrodes.

60 3. In a vacuum circuit breaker, an evacuated enclosure, a plurality of spaced superimposed annular barriers mounted on the

walls of the enclosure and having substantially centrally disposed aligned openings extending transversely of the enclosure, and a pair of relatively movable contacts disposed to draw an arc in a zone between at least two 70 of the barriers so that the arc is substantially surrounded by the boundaries of the said openings, the boundaries of said openings being spaced from the electrodes a sufficient distance to prevent contact of the arc drawn between the electrodes with the barriers, and the barriers being so positioned as to intercept electrons and gases radiated from the arc toward parts of the enclosure unshielded by the electrodes. 80

In testimony whereof, I have hereunto subscribed my name this 8th day of August, 1928.

OTTO H. ESCHHOLZ.
